UNITED STATES PATENT OFFICE.

ROSS VAUGHAN, OF PITTSBURGH, PENNSYLVANIA, ASSIGNOR TO THE EX-EL COMPANY, OF PITTSBURGH, PENNSYLVANIA, A CORPORATION OF DELAWARE.

COIN-CONTROLLED VENDING MACHINE.

Application filed April 21, 1925. Serial No. 24,856.

My invention relates to coin-controlled vending machines and more particularly to machines for vending bottled liquids together with tubes or straws through which the purchasers may suck the liquid from the bottles.

It is one of the objects of this invention to provide a coin-controlled machine which will, upon the deposit of a suitable coin, 10 make accessible a bottle of liquid and a straw or tube for sucking the liquid from the bottle. Another object relates to means for closing the coin-slot when no bottle is in delivery position. Another object relates to 15 means for preventing the operation of the machine by the use of rods or wires. Other objects appear hereinafter.

Referring to the accompanying drawings, Fig. 1 is a front view of a machine containing my invention; Fig. 2, a vertical section on the line II—II of Fig. 1; Fig. 3, an elevation showing the inner side of a panel bearing the coin-controlled mechanisms for three delivery devices; Fig. 4, a top plan view of Fig. 3; Fig. 5, a vertical section through one of the coin-chutes and coin-operated levers, and the adjacent portion of the casing; Fig. 6, a vertical section through the straw-delivery device; Fig. 7, a plan view of Fig. 6 and 25 the coin-controlled mechanism co-operating with the straw-delivery device; Fig. 8, a vertical section on the line VIII—VIII of Fig. 6; and Fig. 9, a detail view on the line IX—IX of Fig. 6 showing a portion of the 30 means for operating the straw-delivery device.

This application relates to improvements on and additions to the mechanism shown and described in my application Serial Number 425,877, filed November 20, 1920, and 40 renewed April 14, 1925.

On the drawings, 1 designates the casing which encloses the several coin-controlled bottle-delivery devices, the straw-delivery 45 mechanism, magazines for the bottles and straws, storage for additional filled bottles and for empty bottles, and cooling means for the filled bottles.

The front side 2 of the casing has the doors 50 3, 4, and 5, one above another, all constructed and operated in the same manner, so that a description of one door and its associated elements will suffice for all. The door 3 forms the front wall of a bottle-delivery 55 device, 6 representing the bottom of the

delivery device. The door and the bottom are connected together at about a right angle at the lower edge of the door. The door is pivoted at that angle as shown in Fig. 2. The delivery device has the end 60 members 7 and 8. A bottle 9 ready for delivery to a purchaser lies between the members 7 and 8 and in the angle made by the door 3 and the bottom 6. A bottle in the delivery device lies on the flap or movable 65 member 10, which consists of a sheet metal strip pivoted at its inner edge to the bottom 6 and held upon the bottom by a bottle 9 in the delivery device.

At the rear of each delivery device is a 70 magazine 11 having an inclined floor 12 with its lower front end arranged to deliver the bottles 9 automatically one at a time to a delivery device when its door or front wall is closed. The rear edge of the bottom 6 has 75 a downwardly turned flange or member 13 which cuts off or holds back the second bottle when the delivery device is swung so as to bring the top edge of the door 3 in front of the casing 1 where the bottle in the delivery 80 device may be removed by the operator who, after the deposit of a proper coin, has pulled the door by the handle 14. The bottles may be arranged in more than one layer by providing a stop 15 so as to engage the front 85 bottle of each layer above the first.

Substantially opposite each door 3, 4, and 5, and in the front 2 is a coin-slot 16 which directs a coin into a chute 17 arranged to deliver the coin to a door-unlocking means. 90 The chutes and the coin-operated means for the several delivery devices are alike and arranged one above another. Only one coin-chute and coin controlled means will be described.

The coin-chute 17 is composed of sheet-metal sides spaced apart the thickness of the coin to be used, the front edge of the chute next to the casing 1 being open and the rear edge being closed above by the downwardly 100 and inwardly inclined wall 18, and below by the downwardly and forwardly inclined wall 19. The upper end of the chute stands just back of the coin-slot 16 so that a coin deposited through the coin-slot will roll down between the wall 18 and the inclined floor 20 punched out of one of the side walls of the chute, and thence down the wall 19 and through the open bottom of the chute to the 105 forked coin-operated lever 21, on which the 110

coin rests with its upper edge still in the chute. The rear wall of the coin-chute has the openings 22 through which wire, inserted through the coin-slot for the purpose of 5 fraudulently operating the lever 21, will extend, thereby directing the wire away from the said lever.

The coin-lever is carried by the pivot 23 supported by the bracket 24 secured to the 10 front 2. The weight of the coin on the lever 21 depresses its forked end so that the upper edge of the coin is slightly above the lower end of the chute and so that the other end of the lever is lifted out of the locking notch 15 26 in the end 7 of the delivery device. The lever is prevented from moving so as to release the coin by the spring 25 having a portion bearing on the end of the lever nearest the delivery device. At the rear edge 20 of the notch 26 there is a cam 27 on the end 7 of the delivery device, this cam being rounded next to the lever 21 and extending above the lever when it is tilted by the weight of a coin. When the delivery device 25 is rotated as shown by the door 3 in Fig. 2, the cam 27 operating on the under side of the lever forces it still farther upwardly against the tension of the spring 25, and causing the forked end of the lever 21 to be 30 lowered and the coin to be tilted into the chute 28 whence it falls through the chutes 29 and 30 into the coin-receptacle 31 below the bottom inclined floor 12. When the coin escapes the spring 25 returns the lever 21 35 to its horizontal position beneath the chute 17. The coin rests with its edges engaging the fork members of the lever 21. The tilting of the lever by the weight of the coin tilts the coin so that, when it is released, it 40 will tilt to the left (looking at Fig. 3) into the chute below rather than to the right whereby it might fall beyond the chute. Coins falling from the middle lever 21 fall into the chute 29 and through the chute 30, and coins falling from the lowest lever 21 45 fall into the chute 30.

At the rear of the front 2 are a number of sheet-metal levers 32, all alike, one above another on separate pivots and designed each 50 to close a coin-slot 16. Each lever is angular or somewhat L-shaped, and pivoted at its angle as shown at 33. The upper end of each lever is held across its associated coin-slot 16 by a spring 34, which like the springs 55 25 have each one end fastened to a vertical flange 35. The inner end of each lever has an upstanding member 36 which extends up through the bottom 6 of its associated delivery device when the latter is closed, and engages the lower face of flap 10, so that, when a bottle 9 rests on the flap, the member 36 60 is depressed and the upper end of the lever 32 is held away from the slot 16. When the delivery device is operated, the flap moves 65 with the delivery device, allowing the spring

34 to close the coin-slot. When a delivery device is closed and no bottle rests on the flap, the member 36 extends up through the bottom 6, and the corresponding coin-slot remains closed, so that a coin may not be forfeited by being inserted in the slot. 70

Above the upper magazine 11 is an ice compartment 37 having the perforated floor 38 or the like for blocks 39 of ice. The cold air and drip from the ice passes over the 75 bottles in the magazines 11 and through the perforated floors 12 to the storage compartment 40 in which the water is held for cooling additional bottles of fluid standing in the water. 80

In the upper portion of the casing 1 is a magazine 41 for suction straws or tubes 42 to be inserted into the bottles for sucking out their contents. The straws are laid parallel in the magazine 41 and at right angles 85 to the front 2. The stationary member of the magazine 41 comprises an outer member 43 lying next to the casing 1 and an inner member or wall 44 parallel therewith, but having its lower end curved outwardly to 90 form a flange 45 and terminating somewhat below the outer member 43, which has its lower portion inclined downwardly toward the inner member 44 to form the fixed portion 46 of the bottom of the magazine. 95 Shortly before the bottom 46 reaches the center of the magazine it descends to form the shoulder or guide 47, from the bottom of which it extends a short distance toward the flange or guide 45. This extension marked 100 48 forms with the guide 45 and the shoulder 47 bottom and lateral rests and guides for the movable member 49 of the magazine 41. 105

The member 49 is made of sheet-metal. Its bottom is inclined and has its upper edge 110 lying on the member 48 and against the shoulder 47 and its lower end resting on the flange 45. From the flange 45 the member 49 turns back parallel with and above its bottom so as to form a supplementary inclined magazine or chute in which a single 115 inclined layer of straws lies, the bottom straw lying in line with the opening 50 in the front 2. Before reaching the shoulder 47, the member 49 turns back toward the side member 44 and then extends up along that member as the inner terminal wall 51 of the member 49. The member 51 is free from the wall 44 except at its upper edge where it has a small flange 52 bearing on 120 the wall 44 to lessen friction. 115

Suspended from the chains or links 53 secured to the wall 51 is a straw agitator 54, which is a sheet of metal lying parallel with the wall 51 and near its inner surface down to about the level where the lower edge of the vertical wall 51 begins. From there the agitator is inclined parallel with the member 49 until it reaches the angle 55 of the member 49, where it turns downwardly as 130

the member 56 and terminates about the diameter of a straw from the bottom of the member 49, leaving a space two or three straws wide between the member 56 and the shoulder 47 or the inner edge 57 of the member 49.

58 is a vertical rock-shaft mounted in the casing 1 and provided with horizontal arms 59 connected by chains 60 or the like to the 10 ends 8 of the delivery devices, so that, when the doors 3, 4, or 5 are opened, the chains will cause the shaft 58 to rotate. The upper end of the shaft has the arm 61 which is connected by the link or chain 62 to one 15 end of the spring 63, having one end secured to the casing 1. The end of the spring attached to the link 62 is connected to the lug 64 carried by the bottom of the movable magazine member 49.

20 The straws preferably have their ends close to the ends of their magazine, the front 2 being the front end of the magazine and the wall 65 being the rear end. The magazine member 49 has a rear or inner extension 25 66 below the bottom straw in this member. This extension projects out through a hole 67 in the wall 65 when the member 49 is in its rear position against the wall 65. The extension has a small upstanding lug or hook 30 68 of a size to engage the end of the bottom straw only and force it for a short distance through the hole 50 when the member 49 is moved toward the front 2.

A proper coin having been inserted 35 through one of the coin-slots 16 runs down the adjacent chute and falls upon a lever 21 and unlocks the corresponding delivery device, as already described. The proper door is drawn out to make the corresponding bottle 40 9 accessible to the depositor of the coin. As the door is operated the associated chain 60 causes the shaft 58 to rotate, the arm 61 causing the movable magazine member 49 to move from the wall 65 to the position shown 45 on Fig. 8, during which time the lug 68 pushes a straw through the hole 50. At the same time the agitator 54, which was at first suspended by the chains 53 hanging vertically, moves with the member 49 toward the front 2 until the projection 69 engages the front 2. Further movement of the member 49 causes the agitator to be lifted slightly causing the straws to be slightly moved to facilitate their feeding downwardly. When 50 55 the member 49 is moved by the spring 63 toward the wall 65, the agitator first drops slightly and then moves with the member

49 toward the wall 65. At the same time the lug 68 rides beneath the lowest straw and through the hole 61. The straws drop so 60 that the end of the lowest one is in the path of travel of the lug 68 at the next operation of the member 49.

The bottle-caps may be removed by any suitable cap-puller 72 located above the 65 chute 69 down which the caps fall into the casing, and empty bottles may be deposited in the compartment 70 in the bottom of the casing through the opening 71.

This application is a copy of my application Serial No. 521,897, filed December 12, 1921, as the same was when allowed March 6, 1923 and inadvertently allowed to lapse March 6, 1925.

I claim—

1. In a dispensing machine, a straw magazine having a bottom member movable lengthwise of the straws, means carried by the said member for moving a straw therewith, an agitator for the straws carried by 80 the said member and movable transversely thereof, a bottle-delivery device, means for operating the said device, a rock shaft operated by the said device, and connections 85 whereby the operation of the said shaft operates the said member.

2. In a dispensing machine, a straw magazine having a movable member, means carried thereby for moving a straw longitudinally with respect to other straws, an agitator member for the straws freely suspended on the said movable member, means for stopping the conjoint travel of the said members whereby the agitator member is caused to move transversely during the further travel of the member not stopped, a bottle-delivery device, means for operating the said device, a rock shaft operated by the said device, and connections whereby the operation of the said shaft operates the said member.

3. In a dispensing machine, a straw magazine, a movable member for moving the straws one at a time longitudinally, a rock-shaft, a bottle-delivery device, means for causing the operation of the said device to rock the shaft, means for causing the rocking of the shaft to operate the said movable member, and means for operating the bottle-delivery device.

In testimony whereof, I affix my signature.

ROSS VAUGHAN.
